(57) CLAIM

The ornamental design for a foot warmer, as shown and described.

DESCRIPTION

FIG. 1 is a front elevation view of a foot warmer showing the new design;

FIG. 2 is a right side elevation view thereof;

FIG. 3 is a left side elevation view thereof;

FIG. 4 is a bottom plan view thereof;

FIG. 5 is a top plan view thereof;

FIG. 6 is a rear elevation view thereof; and,

FIG. 7 is a front, top, and left side perspective view thereof.

The portions of the design shown in broken lines are portions of the foot warmer that form no part of the claimed design.
